CANOPY FOR EXTERIOR LIGHTING FIXTURES OR THE LIKE

John O. Simonds, 17 Penhurst Road 15202; Philip D. Simonds, Brightwood Trail 15237; and Geoff Rausch, 101 Thompson Drive 15229, all of Pittsburgh, Pa.

Filed Sept. 15, 1969, Ser. No. 19,322

Term of patent 14 years

Int. Cl. D26—03

U.S. Cl. D48—31

FIG. 1 is an elevational view of a canopy for exterior lighting fixtures or the like showing our new design; FIG. 2 is a reduced top plan view thereof;

FIG. 3 is a bottom perspective view thereof, being fragmentarily shown for convenience of illustration.

The exterior lighting fixture is shown in broken lines in FIG. 3 for illustrative purposes only.

We claim:

The ornamental design for a canopy for exterior lighting fixtures or the like, as shown and described.
